of Albany, and State of New York, have invented or produced a new design for an ornamental Cooking Stove, and I do hereby declare that the accompanying drawings are full and accurate representations thereof: Fig. 1 being a front: - Fig. 2, a side, and Fig. 3, a rear view. Both sides bear the same figures - W is a section of the mouldings upon the edges of the oven and fire doors: & those of the pannels at the back of the stove. Y of the narrow pannel over the front fire doors, and $\frac{1}{2}$ those of the two pannels VV upon each side of the same - The pannels are filled with ornamental figures composed of scrolls and foliage, not easily described in words, but fully exhibited in the drawings.

What I claim as my invention and desire to secure by letters patent is, the combination and arrangement of ornamental figures, exhibited in the accompanying drawings forming a design for an ornamental cooking stove.
